UNITED STATES PATENT OFFICE.

SIVIL PAULSON, OF ST. PAUL, MINNESOTA.

CARTRIDGE-TUBE FILLER.

1,340,737.

Specification of Letters Patent. Patented May 18, 1920.

Application filed July 31, 1919. Serial No. 314,519.

To all whom it may concern:

Be it known that I, SIVIL PAULSON, a subject of the King of Great Britain, residing at St. Paul, in the county of Ramsey and 5 State of Minnesota, have invented a new and useful Cartridge-Tube Filler, of which the following is a specification.

This invention relates to means for loading the magazines of small fire arms, especially such as are used in shooting galleries. 10 In said places it is customary to speed the loading of the magazines by keeping one or more special tubes filled with cartridges, and empty one of them at a time into the magazine of the gun; but such special or conveying tubes have heretofore been filled by hand, which is too slow a process when the shooting gallery has a great number of visitors desiring to practise shooting. To over- 15 come this and to economize on hired help to keep the tubes filled, I provide a device for filling the tubes very quickly. Said device and its operation is illustrated in the accompanying drawing, in which—

20 Figure 1 is a side elevation of the filling device with some cartridges in it and a tube in position to be filled. Fig. 2 is a top view of the front portion of Fig. 1. Fig. 3 is a section on the line 3—3 in Fig. 2. Fig. 4 is 25 a modification of the lower portion of Fig. 3. Fig. 5 is a bottom end view of the tube 14 in Fig. 1. Fig. 6 is Fig. 5 modified, or a view of the upper end of the tube 14 in Fig. 7. Fig. 7 is a side view of a portion of a 30 gun with the magazine filling tube in position to fill the magazine.

Referring to the drawing by reference numerals, 8 designates the barrel, 9 the tubular magazine and 10 the slidably handle by 35 which the breech mechanism of the gun is operated so as to eject the empty cartridges and move other cartridges into position for firing. Said mechanism and the usual spring-pressed rod 11 for chasing the car- 40 tridges from a tube 12 toward the breech of the gun, and the operation of said parts, are so well known that I need not here further describe the same.

As already stated, under ordinary circum- 45 stances the cartridges are inserted one by one into the magazine 9 through a side aperture 13, (which aperture in that case is much smaller than the one I have shown) and in some cases said aperture is enlarged and a 50 tube 14 employed for conveying a charge of cartridges into the magazine, the tube being

first charged with say ten to thirty cartridges and then placed at the aperture and turned bottom upward. Said tube may have its bottom formed either of a cross bar 15, as in 60 Figs. 6 and 7, or it may be formed of a side portion, 15^x, of the tube, cut loose as at 16 in Fig. 1 and pressed inward as shown in Fig. 5. In either case the bottom is skeletoned so as to admit air freely into the tube and thereby allow the cartridges to drop out quickly. 65

The device by which I fill such tubes comprises a hopper 17 of oblong form and almost V-shaped in cross section, and having its narrow bottom, 18, provided with a longitudinal slot, 19, for the cartridges 20 to hang down through, with their rims 21 riding on the adjacent edges of the bottom or its slot. 70

The ends 22 of the hopper may stand 75 about vertical and one of them is provided with holes for screws 23 by which the hopper may be secured to a wall or similar object, 24.

The outer or front end of the hopper is 80 provided with an aperture 25 (see Fig. 3) for the rim of each cartridge to escape through; and close below said aperture or notch the bottom 18 extends, as 18^a, beyond the hopper and has its slot 19 enlarged at 85 19^a (see Figs. 2 and 3), for the escape of the rims 21 of the cartridges as they drop downward into a short sleeve 26, which is fixed below the part 18^a and has a rearward groove forming an incline 27, by which to 90 aid the lower end of each cartridge into the sleeve and prevent both the point and the rim of the cartridge from catching upon the bottom edge of the inlet through which it entered the tube, said groove forming an 95 inclined chute open rearwardly near its top. The opposite side of the sleeve is provided with a guard 19^b to guide the cartridge rims down into the sleeve.

Secured with their upper ends to opposite 100 sides of the sleeve are two depending spring arms, 28, each of which has at its lower end a hook 29 with an inclined face 30, which normally projects through an aperture 31 in the sleeve, so it may be engaged either inside 105 or outside the sleeve. The lower cartridge in the sleeve is normally held by said hooks either in the position shown in Fig. 3 or that in Fig. 4.

In the operation of the device a supply of 110 cartridges is placed in the hopper and tubes like 14 are one at a time placed in telescoping

position to the lower end of the sleeve, either within the sleeve, as in Figs. 1 and 3, or outside the sleeve, as in Fig. 4, and as the tube is pushed upwardly until it stops against a shoulder, 26^a (see Fig. 1), its upper end engages the inclined faces 30 and spreads the hooks 29 so that the cartridges, which are being stirred forward in the hopper by one hand, while the tube 14 is held in the other hand, fill the tube almost in an instant. As the filled tube is lowered and removed the spring arms 28 will automatically close the hooks 29 sufficiently to prevent escape of cartridges from the sleeve until the next tube, 14, is placed in position and thereby automatically spreads the hooks.

After the operator has thus filled a number of tubes sufficient to last for a day or so, or until he may have leisure time to use for filling more of them, he needs only to invert one of said tubes and thus fill any magazine, 9, in an instant. All he has to do is to pull upward at the head 12^a so as to pull the spring-containing tube 12 and spring-pressed rod 11 out of the way from the inlet 13 during the moment he empties the tube 14, and then push the tube 12 home again and turn it with the pin 12^b into the notch 12^c of the magazine tube 9.

30 What I claim is:—

A device of the kind described, the same comprising a hopper with a narrow bottom

projecting partly beyond the hopper and 35 having a longitudinal slot for cartridges to drop through and be suspended by their rims upon the edges of the bottom; said projecting portion of the bottom having the slot enlarged so as to let the rims of the 40 cartridge pass through it, a sleeve fixed in vertical position underneath said projecting end of the bottom and having two opposite side apertures, two spring arms fixed on the sleeve and having hooks entering said apertures and provided with inclined faces, a series of cartridge conveying tubes having each one end closed and the other end adapted to telescope with the lower end of the sleeve and spread the hooks by engaging 45 their inclined faces, said spring arms adapted to automatically close the hooks into contact with the lowest cartridge in the sleeve and thereby prevent unwarranted escape of the cartridges from the sleeve, said sleeve 50 having its upper end provided with an enlargement toward the hopper, said enlargement having in its upper portion an inlet notch for the cartridges and below said notch an inclined groove serving to guide the 55 cartridges into the sleeve without allowing them to catch on the notched part of the sleeve.

In testimony whereof I affix my signature.

SIVIL PAULSON.
